FREDERICK A. ANTON, OF TOPEKA, KANSAS

STORE-FRONT AWNING

Application filed July 15, 1929. Serial No. 378,433.

This invention relates to awnings of that class known as lateral-arm awnings which involve the use of jointed arms, which in unfolding spread the fabric and refold when the fabric is rolled up. With this type of awning gravity is ordinarily relied upon to effect the spread of the fabric, and in low awnings the fabric when spread has but slight fall or incline and is not usually stretched as tightly as desirable, and sometimes the force of gravity is not sufficient to fully spread the awning. To overcome this difficulty, it has been proposed to use springs at the junction of the folding arm members to assist gravity in the unfolding of the arms and the consequent spread of the fabric, but I have found that on buildings of the more modern type where space between the window to be shaded and the transom above such window is very narrow, it is impracticable to employ a spring at the point mentioned, as to function satisfactorily it occupies relatively so much vertical space as to inhibit proper enclosure within the small box or housing frequently used for the reception and protection of the awning and arms when not in use, and in low awnings the over-head space, when the awning is spread, is so reduced that the said springs sometimes interfere with pedestrian traffic, especially in instances where a person so carries an object that it projects to a substantially higher plane than the bearer's head.

It has also been found that the variation of tension provided in a structure where the spring occurs at the junction of the foldable members, is too limited for practical service in all connections, as the spring at such point, must have a relatively extended range of uncoiling movement,—180°—to effect the complete unfolding of the foldable arm.

My primary object, therefore, is to provide a spring which aids in the opening or spreading of an awning but which uncoils only about a quarter turn—90°—, in the spreading operation and hence applies a greater force to hold the awning fabric under tension, when stretched, than a spring which uncoils about half a turn, and is so located as to give the attendant greater leverage to

effect the return of the awning to inoperative position; which by reason of more restricted coiling and uncoiling action, is subjected to less strain, and hence has capacity for a longer period of service; and which occupies no space in addition to that required for the folding arm, and hence avoids the necessity of the provision of a box or housing of undesirable size.

Another object is to provide very simple means for effecting adjustments for varying the tension of the spring and for incidentally avoiding the necessity of providing threads or employing a nut for retaining the pivot in place, which unites the foldable arm to the customary carrying bracket. Another object is to provide more accessible means than heretofore, for firmly securing the said bracket at the desired points of rotatable adjustment relative to the customary hanger rigidly secured to the building or within the box or housing hereinbefore mentioned.

With the above mentioned objects in view, the invention consists in certain novel and useful features of construction and combinations of parts as hereinafter described and claimed; and in order that it may be fully understood reference is to be had to the accompanying drawing, in which:

Figure 1 is a fragmental plan view of a hanger and folding arm embodying the invention, the hanger and certain parts associated together being broken away to more clearly disclose their relationship and the folding arm occupying its extended or operative position.

Figure 2 is a side view of the hanger and of a part of the folding arm, the latter, as in Figure 1, being indicated in the position occupied when the awning, not shown, is in stretched or operative position.

Figure 3 is an enlarged vertical section taken on the dotted line III of Figure 1.

Figure 4 is a horizontal section taken on the line IV—IV of Figure 3.

Referring now to the drawing in detail, 1 indicates a hanger adapted to be secured to the front of a building or to the back of a box or housing fastened to a building and adapted to receive and protect the awning when in

operative position, neither the building nor the housing being shown. The hanger is of substantially L-shape in side view and at its outer end terminates in a horizontal head 2 which internally tapers from each end at 3, as indicated in the broken part of the hanger, disclosed by Figure 1. The head is also provided with a boss 4 and mounted in said boss is a clamping screw 5.

10 A forked bracket 6 which stands in a position more or less inclined upwardly and outwardly according to the pitch or inclined of the awning when in use is forked to provide an upper and a lower arm, and has a conical 15 stud 7 which projects into the head 2, and has a cross partition 8. An opposing conical stud 9 projects into the head 2 from the opposite end thereof and also has a cross partition 10. The bracket fits against the opposing end 20 of the head, and to clamp it firmly in place, a headed bolt 11 extends through the partition 8 and the partition 10 and is engaged at its outer end by a nut 12. As thus far described the parts correspond to analogous features of my co-pending application Serial No. 320,611.

It has been found essential in awnings of this character to provide means for more dependably guarding against rotatable movement of the bracket than by the bolt and nut connection above mentioned. In my co-pending application provision was made for the purpose mentioned, but I have found that a more simple and equally effective means for 30 preventing rotation of the bracket where the same has a conical stud, the hanger a head for receiving the stud, and means such as the opposing stud and bolt and nut mentioned, for preventing endwise movement of the said 35 conical stud, is to employ a simple clamping screw, as such with the parts correlated as explained, can be caused to impinge tightly on the stud 7 and thus, in cooperation with the clamping action of the nut and bolt, guard 40 against accidental rotatable movement of the bracket, and such clamping screw is easily 45 and readily accessible regardless of whether the awning is in operative position or not.

The upper side of the upper arm 13 of the 50 bracket is formed with a circular recess 14 and axially of said recess, said arm and the lower arm are provided with circular openings for the reception of a pivot 15, having a head 16 by which it may be readily turned by 55 a wrench. Below the head the pivot has a circular enlargement 17 to fit in the circular recess 14, with its upper surface flush with the non-recessed portion of the upper arm of the bracket. The circular enlargement of 60 the pivot is provided with a circular series of openings 18, preferably in its peripheral edge, and any one of said openings is adapted to be engaged by a locking screw or pin 19 mounted in the upper arm of 65 the bracket and disposed so that its head

shall overlie the enlargement of the pivot and thus serve the dual function of preventing rotation and upward movement of the pivot, which therefore needs no nut or the like, to retain it against accidental dislocation from 70 position.

The pivot at its non-threaded end is provided with a longitudinal channel 20 for engagement by an arm 21 formed at one extremity of a coil spring 22. The spring at the extremity mentioned is formed with an inner coil 23 lying within and in juxtaposed relation to the adjacent coil so that the latter may function as a guard against such outward movement of the extremity of the inner coil 24 as would disengage its arm 21 from the pivot bolt. The major portion of the spring corresponds in diameter to the coil which encloses the said inner coil, and at the opposite end the spring terminates in an arm 24 which bears against the inner member of a folding arm composed of said inner member 25 and an outer member 26, the outer member being adapted for attachment to the pole of the curtain, not shown, as conventional in this class 90 of awning.

As the body portion of the spring is of substantially greater diameter than the pivot, a filling sleeve 27 (omitted from Figure 4) is mounted on the pivot and standing on the inner coil 23, substantially fills the spring. The use of this sleeve is desirable as it permits of the employment, without undue lateral bending or movement, of a relatively large spring. Such a spring is desirable because it not only makes provision for the use of an inner coil at the end anchored to the pivot, but has a minimum compressive or torsional action in effecting the opening or unfolding of the foldable arm even where the awning when stretched, occupies a position inclined but little from the horizontal.

It will be understood of course that when the awning is in inoperative position, the arm member 25 projects to the right (with reference to Figure 1) and stands in a position about parallel and almost in alignment with the axis of the bracket, and that the other member is folded back against the outer side of member 25, the curtain at such time being rewound upon the customary roller, not shown.

Assuming that the tension of the spring is excessive for an awning having a particular incline when in operative position, the operator will first permit the folding arms—there being two or more of these for each awning, as of course will be understood,—to assume the outstretched position shown, because if he removes the locking pins 19 when the 110 springs are under the greatest tension, that is when the awning is in inoperative position, it would be necessary to engage a wrench with the head of each pivot to prevent free turning movement thereof. With the fold- 120

able arms outstretched however, and the springs therefore at weakest tension, each locking pin can be readily withdrawn and a wrench applied to the head of the associated pivot to restrain the same from unrestricted 5 turning movement by the spring, but permit the pivot to turn until the spring has relaxed its pressure to the desired extent. When this result is attained, the nearest peripheral opening of the enlargement of the pivot is brought 10 to register with the opening in the upper arm of the bracket 6, and the locking pin is engaged with such peripheral opening and re-engaged with the opening of the bracket.

Where it is desired to increase the tension 15 the same manipulation is followed, except that the force must be applied on the wrench to overcome the resistance of the spring for increasing the tension thereof. When the required increase of tension is obtained, the 20 nearest opening of the pivot enlargement will, as explained, be brought into register with the opening in the upper arm of the bracket, and the locking pin resecured in position.

From the above description it will be apparent that I have produced an awning embodying the improvement set forth as desirable in the statement of the object of the invention, and which may be readily modified 30 in various details within the spirit and scope of the appended claims.

I claim:

1. In an awning, a bracket, a substantially 35 upright pivot carried by the bracket and provided with an enlargement resting on the bracket and equipped with a circular series of openings, a screw engaging the bracket and extending through one of the openings of 40 said enlargement and provided with a head overlapping the enlargement to prevent turning or upward movement of the pivot, a foldable arm pivotally mounted at its inner extremity, on said pivot, and a spring coiled 45 around and secured at one end to the pivot and at the other end engaging the foldable arm adjacent its pivoted extremity and tending to unfold the arm.

2. In an awning, a horizontally forked 50 bracket, a pivot extending through the bracket across the fork thereof and having a head at one end and a longitudinal channel opening through its non-headed end, means to hold the pivot against accidental rotation, 55 an arm mounted on the pivot for swinging movement, and a coil spring loosely enclosing the pivot within the fork of the bracket and at one end engaging said arm and tending to swing the same in one direction; the opposite 60 end of the spring having a double coil, one within and juxtaposed to the other, the inner one terminating in an inwardly-projecting arm engaging the channel of the pivot and held therein by the enclosing coil.

3. In an awning, a horizontally forked

bracket, a pivot extending through the bracket across the fork thereof and having a head at one end and a longitudinal channel opening through its non-headed end, means engaging the head of the pivot to hold the latter 70 against accidental rotation, an arm mounted on the pivot for swinging movement, and a coil spring loosely enclosing the pivot within the fork of the bracket and at one end engaging 75 said arm and tending to swing the same in one direction; the opposite end of the spring having a double coil, one within and juxtaposed to the other, the inner one terminating in an inwardly-projecting arm engaging the channel of the pivot and held therein 80 by the enclosing coil; and a sleeve fitting on the pivot within the spring and resting on the said inner coil thereof.

4. In an awning structure, a support, a pivot carried by the support and provided with an enlargement having a circular series of openings, means secured to the support and overlapping the said enlargement and detachably engaging any one of said openings, an arm pivotally mounted on the pivot, 85 and a spring mounted on and secured at one end to the pivot and engaging said arm and tending to swing the latter on the pivot.

In testimony whereof I affix my signature.
